UNITED STATES PATENT OFFICE.

MAX BENNO FRITSCHE, OF NEW YORK, N. Y.

TOY.

SPECIFICATION forming part of Letters Patent No. 535,896, dated March 19, 1895.

Application filed November 9, 1894. Serial No. 528,274. (No model.)

To all whom it may concern:

Be it known that I, MAX BENNO FRITSCHE, a citizen of the United States, and a resident of New York, county of New York, and State 5 of New York, have invented a certain new and useful Improvement in Toys, of which the following is a specification, reference being had to the accompanying drawings, forming a part thereof, in which similar letters of reference 10 indicate corresponding parts in both figures.

This invention relates to toys, and has for its object to provide a simple, cheap, readily constructed and perfectly operating device of this character which will exhibit a prize-fight 15 or contest, and by oscillating or otherwise manipulating which the figures forming part of the device may be caused to assume the actions of boxers striking each other and avoiding blows.

20 The invention consists in the novel construction and arrangement of parts hereinafter more fully described.

In the accompanying drawings: Figure 1 is a perspective view of a device embodying my 25 invention. Fig. 2 is a plan view of the same, with the body coverings of the figures removed.

In the practice of my invention I construct a 30 flat rectangular base-piece A, of wood, straw-board, or other material, to each corner of which I affix a post B, said posts being connected by cords C, C', extending through the same near the top and bottom. Midway between the center of the base A and each of its 35 ends are secured two blocks or wooden shoes D having spindles D' projecting upwardly therefrom, surrounding which, and secured to the shoes, are spiral springs E of greater diameter at top than at the bottom, comprising 40 legs, and having their upper ends inserted continuously through a flat pasteboard or other strip F, of a form to correspond with the outlines of the head and body of a man, which said strip is mounted between the two adjoining 45 springs E and supported above the same in the manner stated.

Each face of the heads F' of the strips F has marked thereon the representation of the features of a man, preferably of a boxer of well-known reputation, and at the junction of the 50 strip F with the springs E, said strip has secured thereto a paper covering G, extending

downwardly around each of the said springs, in imitation of a pair of tights.

Upon either side of the strips F, near the 55 top of the main portion thereof, are secured spiral springs H, H', comprising the arms of the figures, the ends of said springs being inserted through the strip F, extending rearwardly, and secured together. The arms H, 60 which are upon the right-hand side of each figure, extend horizontally in a straight and slightly outward direction toward the opposite figure, and the arms H' project diagonally downward and outward throughout half their 65 length, and thence forwardly and upwardly at right angles, and slightly inwardly. All of the said springs H, and H' have secured upon the free ends thereof substantially spherical padded bodies I, in imitation of hands having 70 boxing gloves thereon.

The operation of the device will be readily understood from the foregoing description, taken in connection with the accompanying drawings. The base A being held in the hand, 75 and oscillated or sharply shaken longitudinally, the springs E yield or swing from their fulcrum joints on the spindles D'. The figures are thrown toward each other, or one forwardly and the other rearwardly as if resisting an attack, the gloves or bodies I of the springs H and H' meeting and lending the appearance of a prize fight or boxing contest, this being heightened by the form of the springs H, representing the right arm shot 80 out, and the springs H', representing the left arm crooked and held as if to ward off the blows. It will be observed that the said springs H and H' will not only yield longitudinally to cushion the striking of the figures but will also yield laterally, and the spring H often pass inwardly of the opposing spring H' owing to the relative arrangement of said springs and strike the body of the figure. 85

I do not confine myself to the exact construction and formation of any of the parts herein set forth and illustrated, except as such are hereinafter specified in the claims hereto annexed.

Having thus fully described my invention, what I claim as new, and desire to secure by Letters Patent, is—

1. A toy of the character described compris-

ing a flat base, spiral springs secured upon said base to form the legs of two figures, substantially rigid bodies secured to said springs, each body being formed to represent the trunk and head of a man, spiral springs secured to each side of the figures, one projecting forwardly in a substantially straight direction, and the other projecting diagonally outwardly and upwardly; and padded substantially spherical bodies secured to the free end of each of the arms.

2. A toy of the character described comprising a flat base, two pairs of shoes secured to said base, spiral springs projecting upwardly therefrom, a flat strip secured between each of the springs and formed to represent the body and head of a man, a flexible covering secured to said strip and surrounding the upper portion of the springs, spiral springs secured to each side of the figures, one projecting forwardly in a substantially straight direction, and the other being angular; and padded bodies upon the free end of each of the arms.

25 3. A toy of the character described, compris-

ing a flat rectangular base having posts projecting upwardly from each corner thereof, and cords connecting and inserted through said posts, two pairs of shoes secured to the base, spiral springs projecting upwardly therefrom, each pair of the springs having a flat strip secured thereto above and between the same, said strip being formed to represent the body and head of a man, a paper covering secured to said strip and surrounding the upper portion of the springs, spiral springs secured to each side of the figures, one projecting forwardly in a substantially straight horizontal direction and the other projecting diagonally outwardly and upwardly, and padded substantially spherical bodies secured to the free end of each of the arms.

In testimony that I claim the foregoing as my invention I have signed my name, in presence of two witnesses, this 7th day of November, 1894.

MAX BENNO FRITSCHE.

Witnesses:

T. WALSH,

JOHN M. DUMER.
